WALKING HORSE

James V. Card, La Grange, Tex., assignor to
Texas Toy Horse Manufacturing Company,
Ltd., La Grange, Tex., a corporation of Texas

Application March 1, 1949, Serial No. 78,915

3 Claims. (Cl. 280—1.203)

1

This invention relates to a mechanical toy, and more particularly to a mechanical hobbyhorse for children.

The object of this invention is to provide a mechanical hobbyhorse which will provide entertainment for a child.

Another object of the invention is to provide a toy vehicle having the configuration of a horse, and which will simulate the movements of a horse when in use.

A further object of the invention is to provide a mechanical hobbyhorse which is adapted to be propelled by a child and which will provide suitable exercise for the child.

Still a further object of the invention is to provide a mechanical hobbyhorse which is extremely simple and inexpensive to manufacture.

Other objects and advantages will be apparent during the course of the following description.

In the accompanying drawings forming a part of this application, and in which like numerals are employed to designate like parts throughout the same:

Figure 1 is a side elevational view of the mechanical hobbyhorse according to the present invention;

Figure 2 is a side elevational view of the horse, with parts broken away and in section;

Figure 3 is a sectional view taken approximately on the line 3—3 of Figure 2 with the legs in a different position;

Figure 4 is a horizontal sectional view of the rear portion of the mechanical horse, and with the rear legs in the position shown in Figure 1;

Figure 5 is a sectional view taken on the line 5—5 of Figure 2;

Figure 6 is a sectional view taken on line 6—6 of Figure 2;

Figure 7 is a horizontal sectional view of the lower portion of the hinge connection between the neck and body;

Figure 8 is an enlarged sectional view of one of the clutch assemblies for the left front wheel;

Figure 9 is a sectional view taken on the line 9—9 of Figure 8;

Figure 10 is a sectional view of a portion of one of the clutch assemblies shown in Figure 8;

Figure 11 is a sectional view taken on the line 11—11 of Figure 2;

Figure 12 is a horizontal sectional view illustrating the actuating means for the brake and clutch;

Figure 13 is a view similar to Figure 12 with the horse's neck turned to the right;

Figure 14 is a vertical sectional view illus-

2

trating the position of certain parts of the clutch and brake assembly when the vehicle is being turned to the right.

Figure 15 is a detail view of one of the levers 5 through which the clutches and brakes are operated.

Referring in detail to the drawings, the wheeled vehicle preferably has the external configuration of a horse and includes a body 30 fabricated of 10 plywood or other suitable material. The body 30 is shaped to define a pair of spaced side portions 31 and 32 and supported by the body 30 is a saddle 29 for supporting a child thereon, the saddle 29 being secured to the side portions 31 and 32 by screws 33 or the like. A tail 34, preferably fabricated of rubber to prevent damage to household furniture, projects rearwardly from the body 30 and is secured thereto by screws or other fastening elements 35.

Arranged adjacent the tail 34 and interposed between the side portions 31 and 32 is a support member 36 which is provided with a vertically-disposed bore 31, there being screws 38 for securing the support member 36 to the side portions.

Positioned below the support member 36 is a housing 39 which carries a horizontally-disposed pulley 40, there being a sash cord 41 trained over the pulley 40 for a purpose to be later described. A pin 42 secures the cord 41 to the pulley 40. Projecting upwardly from the housing 39 is a shaft 43 which rotatably seats in the bore 31, and projecting downwardly from the housing 39 is a pair of spaced hind or rear legs 44 and 45 and each leg is provided with a ground-engaging caster wheel 46 on its lower end. There is imparted a lifelike swinging movement to the rear legs 44 and 45 as the vehicle moves, as hereinafter described.

Arranged forwardly of the support member 36 and secured to the side members 31 and 32 by screws 47 is a block 48, Figure 2. An eye bolt 23 projects rearwardly from the block 48 for engagement with an end of a coil spring 49, and the other end of the spring 49 is connected to a cotter

45 pin 50 which extends through a cutout 51 in the support member 36 and also extends through the shaft 43, the spring 49 serving to normally urge the rear legs 44 and 45 straight ahead and into alignment with the body 30. A vertically-disposed, rotatable pulley 52 is supported by the front portion of the block 48 and a strap 53 provided with adjusting buckles 54, Figure 1, is trained over the pulley 52. The free ends of the strap 53 are pivotally connected to stirrups 55

and 56 by means of a pin 57, and the stirrups are adapted to be engaged by the child's feet.

Extending between the side portions 31 and 32 of the body 30 is a horizontally-disposed shaft 58, there being a cotter pin 59, Figure 5, for maintaining the shaft 58 therein. The side portions 31 and 32 are cut away adjacent the shaft 58, as at 60, to permit swinging movement therein of the top members 61 of the front legs 62. There are a pair of these front legs 62 and each embodies a top member 61 which is secured to a link 63 by screws or rivets 64, each of the links 63 having its upper end pivotally connected to the shaft 58. The other end of each of the top members 61 is bifurcated, as at 65, for receiving therein one end of the bottom member 66, there being a pin 67 pivotally connecting the bottom member and top members of each front leg together. A pair of rods 68 and 69 each have one end pivotally connected by a pin 70 to the hoofs of the front legs and the rods 68 and 69 are pivotally connected to the stirrups 55 and 56, respectively, by pins 72. The rods 68 and 69 each have their rear portions bent transversely, as at 73, and the rods terminate in a bent section 74. A pair of crank arms 75 and 76 are pivotally mounted in bearings 77 which are supported in the body 30, and the crank arms 75 and 76 each have their lower ends pivotally connected, as at 78, to the rear ends of the rods 68 and 69, respectively. The sash cord 41 is trained over guide pulleys 21 and the free ends thereof are connected to the crank arms 75 and 76, Figure 3.

A horizontally-disposed front axle 79 is rotatably connected to the lower ends of a pair of legs 25 and 26 which are part of a stationary frame 27 and a pair of cranks 80 and 81 each have an end secured to the ends of the axle 79. The other ends of the cranks 80 and 81 are pivotally connected, as at 82, to the respective bottom members 66 of the front legs. A right front wheel 83 and a left front wheel 84 are rotatably mounted on the axle 79, the wheels each including an outer tread 85, the wheels 83 and 84 being positioned contiguous to the respective cranks 80 and 81.

There is provided a clutch and brake assembly for controlling the movement of the front wheels in order to properly turn or steer the vehicle. This turning movement is controlled by movement of the forwardly-projecting head 86, there being a strap or reins 87 connected to the front of the head 86 and adapted to be gripped by the child rider. A pair of opposed plates or blocks 88 and 89, Figure 7, are arranged in the hollow body 30 and are secured to the side portions thereof. A rocker arm 90 is pivotally connected to the plate 88 by a pin 91 which also extends through a spacer member 15. A second rocker arm 92 is pivotally connected to the other plate 89 by a pin 93. The head 86 is hingedly connected to the vehicle at two points whereby swinging movement about a vertical axis is permitted. Thus, an upper bracket 94 has one end secured to the head 86 by rivets 19, Figure 2, and a pin or bolt 95 pivotally connects the free end of the bracket 94 to the web 96 of the fixed frame 21. A vertically-disposed shank 97 is fixed to the bracket 94 intermediate its ends for a purpose to be later described. A horizontally-disposed brace 98 extends between the legs 25 and 26 and is secured thereto. A second bracket 99 is spaced below the first bracket 94, and is secured to the head 86 by rivets 100, there being a bolt-and-nut assembly 101 pivotally connect-

ing the other end of the second bracket 99 to the brace 98.

The clutch and brake assembly further includes a first lever 102 which projects through the rocker arm 92 and has its upper end bent transversely to define a hook 103 which terminates adjacent the shank 97. The lower end portion of the lever 102, is in the form of an elongated loop which surrounds the axle 79 and contacts with one of the clutch plates 115. A second lever 104 is provided, and this lever projects through the other rocker arm 90 and has its upper end bent transversely to define a hook 105 which is arranged on the other side of the shank 97. The lower end portion of the second lever 104 also has an elongated loop which surrounds the axle 79 and contacts the other clutch plate 115, there being a coil spring 106 connected to the two levers 102 and 106 for normally urging the latter toward each other. Arranged below the spring 106 are horizontally-disposed strips 107 which have their ends secured to the legs of the frame 27. Links 108 have their lower ends pivotally connected to the strips 107, as at 109, and their upper ends pivotally connected to the lever 102. Second links 110 have their lower ends connected to the strips 107, as at 111, and their upper ends pivotally connected to the other lever 104. A horizontally-disposed brake member 112 and 113 are secured to the levers 102 and 104, respectively, and the brake members are mounted for movement into and out of frictional engagement with the front wheels 83 and 84 upon pivotal movement of the levers. The pivotal movement of the levers 102 and 104 is caused by turning the head 86 whereby the shank 97 contacts one of the hooks 103 or 105.

Formed integrally with the left front wheel 84 or secured thereto is a sleeve or hub 114, Figures 2 and 8, which includes a longitudinally-extending central opening 117 for rotatably embracing the axle 79. The exterior of the sleeve 114 is square in cross-section, and slidably arranged on the sleeve 114 is a portion of a disc 115 which is provided with a plurality of spaced holes or openings 116. A collar 117 is keyed to the axle 79 and a pin 118 projects from the collar 117 and is adapted to register with one of the openings 116 in the disc 115 whereby the axle 79 will normally rotate or drive the wheel 84. A cotter pin 119 projects through the axle 79 for supporting the pin 118. A suitable bushing 16 maintains the clutch in assembled relation. The looped end of the lever 102 terminates in the space between the disc 115 and the collar 117 so that upon pivotal movement of the lever 102, the disc 115 will be moved away from the collar 117 so that the pin 118 will be free of the holes in the disc 115, thus enabling the axle 79 to rotate freely in the wheel 84.

There is a second clutch member 120 arranged adjacent the other front wheel 83 for disengaging the front wheel 83 from the axle 79. The clutch 120 has the same structure and function as the previously-described clutch for the wheel 84, but works in the opposite direction.

The operation of the mechanical horse is as follows: The child sits on the saddle 29 with his or her feet in the stirrups 55 and 56. Then, when the child moves his legs, a circular motion will be imparted to the cranks 80 and 81 to thereby rotate the axle 79. As long as the vehicle continues in a straight-ahead direction, the front-wheels 83 and 84 will be driven by the rotating axle 79. To steer or turn the vehicle, as for ex-

ample to turn to the right, the reins 87 are pulled to the right, thus turning the head 86 to the right. This turning of the head from the position of Figure 12 to the position of Figure 14 moves the shank 97 into engagement with the hook 105 and causes the lever 104 to move to the right, which simultaneously actuates the clutch 120 to permit the axle 79 to rotate freely in the right wheel 83 and also moves the brake member 113 into frictional engagement with the right wheel 83 to prevent rotation thereof. Thus, since the left wheel 84 continues to rotate, the vehicle will turn. Similarly, to turn the vehicle to the left, head 86 is moved to the left, whereupon lever 102 will move to the left to thereby compress coil spring 14 and move the disc 115 out of engagement with the pin 118, which is connected to the rotating collar 117. This last-named movement stops the axle 79 from driving the left front wheel 84 and at the same time causes the brake member 112 to engage the left front wheel.

The toy is further constructed so that the legs thereof simulate the lifelike movements of a horse. Thus, the front legs are each made of two members 61 and 66, and these front legs are caused to bend at the pivot points 66 as the cranks 80 and 81 are rotated. The rear legs 44 and 45 swing in an arc, as seen in Figure 4, and this swinging movement is accomplished by means of a sash cord 41 which is trained over the pulley 40 and connected to the moving elements 75 and 76.

As many embodiments may be made of this inventive concept, and as many modifications may be made in the embodiment hereinbefore shown and described, it is to be understood that all matter herein is to be interpreted merely as illustrative and not in a limiting sense.

I claim:

1. A mechanical vehicle having the external configuration of a horse comprising a hollow body provided with a pair of side portions, a saddle supported on said body for supporting a child, a tail fabricated of hard rubber projecting rearwardly from said body, a frame having an inverted U-shape arranged forwardly of said body and secured thereto, said frame embodying a horizontally-disposed web and a pair of spaced legs, a horizontally-disposed brace extending between said legs and secured thereto, a horizontally-disposed axle rotatably mounted in the lower ends of said legs, a crank secured to each end of said axle for rotating the latter to propel said vehicle, a pair of spaced parallel ground-engaging front wheels rotatably mounted on said axle, a pair of front legs each embodying a top member pivotally connected to the complementary side portion of the body and a bottom member having one end pivotally connected to said top member and its other end pivotally connected to said crank, a rod extending rearwardly from each of the bottom members of said front legs and pivotally connected thereto, a block positioned between said saddle and interposed between the side portions of said body and secured thereto, a rotatable pulley projecting forwardly from said block and mounted for rotation about a horizontal axis, a stirrup strap trained over said pulley, a stirrup adapted to be engaged by the child's foot connecting each end of said strap to the complementary rod, a pair of crank bars each having one end pivotally connected to the side portions of said body and their other ends pivotally connected to the complementary rods, a support member arranged rearwardly of said body and secured thereto, there being a vertically disposed bore arranged in said support member, a housing positioned below said support member, a shaft projecting upwardly from said housing and rotatably seated in said bore, a pair of spaced rear legs depending from said housing, a rotatable ground-engaging caster wheel connected to the lower end of each of said legs, a horizontally disposed pulley carried by said housing, a sash cord trained over said lastnamed pulley and having its ends connected to said crank bars whereby a swinging movement is imparted to said rear legs upon movement of said vehicle, a head arranged forwardly of said body and hingedly connected to the web of said frame and to said brace, and means connected to said head for causing turning movement thereof.

to, there being a vertically-disposed bore arranged in said support member, a housing positioned below said support member, a shaft projecting upwardly from said housing and rotatably seated in said bore, a pair of spaced rear legs depending from said housing, a rotatable ground-engaging caster wheel connected to the lower end of each of said legs, a horizontally-disposed pulley carried by said housing, a sash cord trained across said last-named pulley and having its ends connected to said crank bars whereby a swinging movement is imparted to said rear legs upon movement of said vehicle, a head arranged forwardly of said body and hingedly connected to the web of said frame and to said brace, and reins connected to said head for causing turning movement thereof.

2. A mechanical vehicle having the external configuration of an animal comprising a hollow body provided with a pair of side portions, a saddle supported on said body for supporting a child, a tail projecting rearwardly from said body, a frame having an inverted U-shape arranged forwardly of said body and secured thereto, said frame embodying a horizontally disposed web and a pair of spaced legs, a horizontally disposed brace extending between said legs and secured thereto, a horizontally disposed axle rotatably mounted in the lower end of said legs, a crank secured to each end of said axle for rotating the latter to propel said vehicle, a pair of spaced parallel ground-engaging front wheels rotatably mounted on said axle, a pair of front legs each embodying a top member pivotally connected to the complementary side portion of the body and a bottom member having one end pivotally connected to said top member and its other end pivotally connected to said crank, a rod extending rearwardly from each of the bottom members of said front legs and pivotally connected thereto, a block positioned between said saddle and interposed between the side portions of said body and secured thereto, a rotatable pulley projecting forwardly from said block and mounted for rotation about a horizontal axis, a stirrup strap trained over said pulley, a stirrup adapted to be engaged by the child's foot connecting each end of said strap to the complementary rod, a pair of crank bars each having one end pivotally connected to the side portions of said body and their other ends pivotally connected to the complementary rods, a support member arranged rearwardly of said body and secured thereto, there being a vertically disposed bore arranged in said support member, a housing positioned below said support member, a shaft projecting upwardly from said housing and rotatably seated in said bore, a pair of spaced rear legs depending from said housing, a rotatable ground-engaging caster wheel connected to the lower end of each of said legs, a horizontally disposed pulley carried by said housing, a sash cord trained over said lastnamed pulley and having its ends connected to said crank bars whereby a swinging movement is imparted to said rear legs upon movement of said vehicle, a head arranged forwardly of said body and hingedly connected to the web of said frame and to said brace, and means connected to said head for causing turning movement thereof.

3. A mechanical vehicle having the external configuration of an animal comprising a hollow body provided with a pair of side portions, a saddle supported on said body for supporting a child, a tail projecting rearwardly from said body, a frame having an inverted U-shape arranged for-

wardly of said body and secured thereto, said frame embodying a horizontally disposed web and a pair of spaced legs, a horizontally disposed brace extending between said legs and secured thereto, a horizontally disposed axle rotatably mounted in the lower ends of said legs, a crank secured to each end of said axle for rotating the latter to propel said vehicle, a pair of spaced parallel ground-engaging front wheels rotatably mounted on said axle, a pair of front legs each embodying a top member pivotally connected to the complementary side portion of the body and a bottom member having one end pivotally connected to said top member and its other end pivotally connected to said crank, a rod extending rearwardly from each of the bottom members of said front legs and pivotally connected thereto, a pulley arranged between the side portions of said body and mounted for rotation about a horizontal axis, a stirrup strap trained over said pulley, a stirrup adapted to be engaged by the child's foot connecting each end of said strap to the complementary rod, a pair of crank bars each having one end pivotally connected to the side portions of said body and their other end pivotally connected to the complementary rod, a support member arranged rearwardly of said body and secured thereto, there being a vertically disposed bore arranged in said support member, a

5
10
15
